UNITED STATES PATENT OFFICE.

SAM A. WILLSON, OF RUSK, TEXAS.

HORSE-DETACHER.

SPECIFICATION forming part of Letters Patent No. 272,394, dated February 13, 1883.

Application filed November 10, 1882. (No model.)

To all whom it may concern:

Be it known that I, SAM A. WILLSON, a citizen of the United States, residing at Rusk, in the county of Cherokee and State of Texas, have invented certain new and useful Improvements in Devices for Detaching Horses and other Animals from Vehicles, of which the following is a specification, reference being had therein to the accompanying drawings.

10 My invention relates to horse-detaching devices, the object being to provide a device of this character of simple, inexpensive, and durable construction, and adapted to readily disengage the traces from the single-tree.

15 The invention consists in the improved construction and combination of parts hereinafter fully described, and pointed out in the claim.

In the drawings, Figure 1 represents a plan view of a single-tree provided with my improvement. Fig. 2 is a side elevation of the same. Fig. 3 is a sectional view of the end of the wibbilletree.

20 A represents a single-tree pivotally secured in the usual manner to the cross-bar B of the shafts.

25 C represents a loop secured to the upper side of the single-tree, and at its opposite end to the under side of the cross-bar B to limit the movement of the single-tree. The single-tree is provided with the usual spindle or pins, 30 a a, to receive the ends of the traces.

35 C' C' represent sliding detaching-bars, the outer ends of which are bent at right angles to bear against the ends of the spindles a a to securely retain the traces upon the spindles.

40 D D represent collars secured to or formed integral with the detaching-bars C' C', and arranged upon the latter adjacent to their outer angles, so that the collars will surround the outer ends of the single-tree when the traces 45 are attached, and adapted, when the bars C' C' are operated, to disengage the traces from

the single-tree. The bars C' C' are guided upon the upper side of the single-tree by staples or keepers c c, and the inner ends of said 45 bars form opposite right angles C² C².

E represents a bell-crank lever fulcrumed upon the upper side of the single-tree, and having the inner ends of the sliding bars C' C' pivotally secured thereto, as shown. To 50 the forward arm of the lever E is secured one end of a spiral spring, e, the opposite end of said spring being secured to the single-tree. The rear arm of the lever is provided with a perforation, E', to receive a cord adapted to 55 be arranged in easy reach of the driver. The spring e operates to retain the sliding bars C' C' in position, as shown in Fig. 1.

To disengage the trace from the single-tree it is only necessary to operate the lever E, 60 which forces the sliding bar outward thus disengaging the traces.

In connection with my improved device I employ upon the shafts, instead of the usual holdback-strap, open-ended loops or bent bars 65 F F, which allow the holdback-straps to freely slip off.

I claim—

The combination, with a single-tree, of two sliding detaching-bars arranged in guides upon 70 the single-tree, and provided at their outer ends with collars and trace-retainers, while their inner ends are bent to form opposite angles, and are pivoted to a lever, E, a spiral spring, e, secured at one end to said lever, and 75 at the opposite end to the single-tree, to lie parallel with the latter, and a loop, C, substantially as set forth.

In testimony whereof I affix my signature in presence of two witnesses.

SAM A. WILLSON.
